UNITED STATES PATENT OFFICE.

HARRIE C. GREEN, OF HUBBARDSTON, MASSACHUSETTS.

DESIGN FOR A STATUETTE.

Application filed May 28, 1928. Serial No. 26,880. Term of patent 7 years.

To all whom it may concern:

Be it known that I, HARRIE C. GREEN, a citizen of the United States of America, and a resident of Hubbardston, in the county of Worcester and State of Massachusetts, United States of America, have invented a new, original, and ornamental Design for a Statuette, of which the following is a specification.

Reference is had to the accompanying drawings forming part of this specification, wherein—

I claim:

The ornamental design for a statuette as shown.

Signed at New York, in the county of New York and State of New York, this 25th day of May A. D. 1925.

HARRIE C. GREEN.
